US00D920076S

(12) **United States Design Patent** (10) **Patent No.:** **US D920,076 S**
Luebeck et al. (45) **Date of Patent:** **** May 25, 2021**

(54) **LOCKING DEVICE**

- (71) Applicant: **Carrier Corporation**, Palm Beach Gardens, FL (US)
- (72) Inventors: **Jon Marc Luebeck**, Stayton, OR (US); **Bonnie McClure**, Salem, OR (US); **Steve Switzer**, Atlanta, GA (US)
- (73) Assignee: **CARRIER CORPORATION**, Palm Beach Gardens, FL (US)
- (**) Term: **15 Years**
- (21) Appl. No.: **29/728,524**
- (22) Filed: **Mar. 19, 2020**

Primary Examiner — Steven J Czyz*(74) Attorney, Agent, or Firm* — Cantor Colburn LLP**CLAIM**

We claim, the ornamental design for a locking device, as shown and described.

DESCRIPTION

FIG. 1 is a perspective view of a locking device, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is a perspective view of the locking device, shown in use with environment.

The broken lines depict portions of the article and environment that form no part of the claimed design.
